United States Patent Office

Des. 193,924
Patented Oct. 23, 1962

193,924

FAUCET UNIT OR SIMILAR ARTICLE

Millard Fillmore Harty, Jr., Mount Clemens, Mich., assignor to Michigan Brass Company, Grand Haven, Mich., a company of Michigan

Filed Mar. 27, 1961, Ser. No. 64,491

Term of patent 14 years

(Cl. D91—3)

FIG. 2

FIG. 1

FIG. 3

FIGURE 1 is a perspective view of a faucet unit or similar article embodying my new design.

FIG. 4 is a longitudinal section taken on line 4—4, FIG. 1.

The dominant features of my design reside in the portions shown in full lines.

I claim:

The ornamental design for a faucet unit or similar article, substantially as shown and described.
